[57] **CLAIM**

The ornamental design for a portable windshield washer, as shown and described.

DESCRIPTION

FIG. 1 is a front plan view of the portable windshield washer of the present invention;

FIG. 2 is a back plan view of the portable windshield washer of FIG. 1;

FIG. 3 is a left side view of the portable windshield washer of FIG. 1;

FIG. 4 is a right side plan view of the portable windshield washer of FIG. 1;

FIG. 5 is a top plan view of the portable windshield washer of FIG. 1; and,

FIG. 6 is a bottom plan view of the portable windshield washer of FIG. 1.

The tube is shown broken away in FIGS. 1, 2, 5 and 6 to indicate indeterminate length.
